UNITED STATES PATENT OFFICE.

EDSON J. HADLOCK, OF BIG SPRING, TEXAS.

SMOKE AND SPARK ARRESTER AND CONSUMER.

SPECIFICATION forming part of Letters Patent No. 483,055, dated September 20, 1892.

Application filed January 13, 1892. Serial No. 417,915. (No model.)

To all whom it may concern:

Be it known that I, EDSON J. HADLOCK, of Big Spring, in the county of Howard and State of Texas, have invented a new and Improved 5 Smoke and Spark Arrester and Consumer, of which the following is a full, clear, and exact description.

My invention relates to improvements in smoke and spark arresters and consumers, 10 such as are adapted for use on locomotives; and the object of my invention is to produce an apparatus of the character described which may be economically applied to a common locomotive and which will cause the smoke and 15 sparks to be arrested and consumed, thus effecting a saving of fuel and preventing the sparks from setting fire to the surrounding property.

My invention is an improvement on the apparatus for which I obtained Letters Patent 20 of the United States April 7, 1891, No. 450,012, and also on the apparatus for which I applied for Letters Patent of the United States May 29, 1891, Serial No. 394,514, said application 25 having been allowed August 10, 1891.

My invention consists in certain features of construction and combinations of parts, which will be hereinafter described and claimed.

Reference is to be had to the accompanying 30 drawings, forming a part of this specification, in which similar figures of reference indicate corresponding parts in all the views.

Figure 1 is a broken side elevation, partly 35 in section, of a locomotive provided with my improved apparatus. Fig. 2 is a cross-section of the same on the line 2 2 in Fig. 1, and Fig. 3 is a broken plan view of the same.

The locomotive 10 is of the common type, 40 having an extension-front 11, from which extend rearward on each side of the locomotive the return smoke-pipes 12, which have valve-controlling openings into the fire-box, as shown at 13, and which at their rear ends connect by couplings 14, with a pipe 15, coiled within the 45 tank of the tender 16, and the pipe 15 opens, as shown at 17, into a chute 18, leading to the ash-pit. The chute has a water-holding receptacle 19 in the lower part thereof, and the water is pumped from this receptacle by a 50 pipe 20, leading from the water-receptacle to the filtering apparatus in the tank of the tender.

In front of the smoke-box is a swinging damper 21, operated by a lever 22, extending into the locomotive-cab, and beneath the ash-pit is a sliding damper 23, connecting by a rod 24 with a lever 25, which also extends into the cab, so that it may be easily operated. 55

Connected with the steam-dome of the locomotive are pipes 26, which at their lower ends 60 enter the smoke-pipes 12 and terminate in rearwardly-extending jet-pipes 27, adapted to blow the smoke back into the fire-box and keep up a forced circulation when the engine is not working steam. The pipe 26 is controlled by a valve having a rod 28 extending into the engine-cab. 65

The foregoing construction has not been described in detail, as it is similar to the construction shown in my former patents referred 70 to, except that the smoke-pipes connect with the extension front instead of with smoke-boxes in the rear thereof. The extension front 11 is divided transversely, so as to form a rear smoke-box 27^a and a receptacle in front 75 of it by a partition 28^a, which partition has centrally therein a swinging door 29, which enables the interior of the smoke-box to be reached when necessary, and the door should be arranged so as to make an air-tight joint 80

when closed and prevent it from interfering with the draft. Opening from the upper portion of the smoke-box 27^a is a short stack 30, which connects by means of an elbow 31 with a box 32 in front of it, which box connects 85 with the extension front and has an escape-stack 33 opening from its upper portion in front of the elbow 31. In the bottom of the box 32 is an A-shaped deflector 34, which is suspended from its edges by means of suitable bolts 35, and this deflector permits the smoke, sparks, and cinders which issue from the elbow 31 to pass downward into the extension front, and the cinders and sparks cannot rise, as the deflector will stop them; but 90 the very light smoke, which is substantially freed of carbon, will escape through the stack 33. In the bottom of the extension front 11 is a hopper 36, which ranges slightly forward and which is closed by a cover 37, and by 95 means of this hopper the cinders may be withdrawn from the extension front when the latter has become full, or nearly so.

The operation of the apparatus is as fol-

lows: As the smoke and other products of combustion issue from the boiler-flues into the smoke-box 27^a they will pass upward through the rear stack 30 and forward through the elbow 31 to the box 32. Here the light smoke, which contains no carbon or substantially none, will pass up through the escape-stack 33, while the other products of combustion will pass downward over the deflector 34 and into the extension front 11. The deflector will prevent the said products from returning, and the heavier and worthless products—such as the cinders—will settle in the extension front, while the smoke and lighter matter will pass back through the smoke-pipes 12 into the fire-box and be consumed. These smoke-pipes 12 may connect directly with the fire-box or the products may be carried around through the pipe in the tank, as desired.

Having thus described my invention, I

claim as new and desire to secure by Letters Patent—

The combination, in a locomotive having a transversely-divided front extension 11, of a box 32 over the forward compartment, a deflector at the bottom of the box and upper part of said compartment and having its edges spaced therefrom to permit communication between the two, a stack 30, extending upward from the rear or smoke compartment and discharging through an elbow 31 into the top of said box, a stack 33, leading from the top of box 32 in front of stack 30 and of greater diameter than the latter stack, and the pipes 12, leading from the forward compartment rearwardly into the fire-box above its fuel-space, substantially as set forth.

EDSON J. HADLOCK.
